UNITED STATES PATENT OFFICE

2,168,669

ARRANGEMENT FOR DRIVING AUXILIARY
PILOT PUMPS AND SLIPPAGE PUMPS

Walter Ernst, Mount Gilead, Ohio, assignor, by
mesne assignments, to The Hydraulic Press
Corporation, Inc., Wilmington, Del., a corpo-
ration of Delaware

Application September 19, 1935, Serial No. 41,281
Renewed February 11, 1939

6 Claims. (Cl. 103—4)

It is the object of my invention to provide in an integral unit driven from a single source of power the combination of a main hydraulic pump, a slippage pump and a pilot pump.

5 The slippage pump is used to pick up the drainage from the main pump which has drained down into the slippage tank and deliver this drainage to the main tank. Such a slippage pump has heretofore been driven remotely. It 10 has also been necessary to have a pilot pump required to operate the servo-motor or similar control device.

It is preferable to have such pumps all driven in synchronism with one another.

15 It is the object of the present invention to provide for a main pump and to drive off the driving shaft of the main pump a slippage pump as an integral part of the main pump, but mounted thereon in such a way as to be easily replaceable; and to utilize the drive for the slippage 20 pump for operating a pilot pump separately mounted upon the slippage pump.

In particular, it is the object of my invention to provide a radial pump on the drive shaft of 25 which is mounted a driving gear. Associated with this driving gear is an intermediate gear that forms a slippage gear pump. These gears are also utilized for driving a third gear which is mounted on the driving shaft of a pilot pump. 30 I am thereby enabled to utilize the main driving shaft of the main pump for driving both the slippage pump and the pilot pump in synchronism therewith, and to utilize the driving gear connected to the main drive shaft for the dual 35 purpose of acting as a gear pump and acting as a drive for the pilot pump, while at the same time keeping all of the pumps together in a unitary structure but detachable and demountable from one another for assembly, inspection 40 and repair.

Referring to the drawings:

Figure 1 is a perspective of the exterior of the 45 several pumps.

Figure 2 is a section through one end of a main hydraulic pump, the gear slippage pump and the gear drive for the pilot pump.

Figure 3 is a section on the line 3—3 of Figure 2.

Figure 4 is a diagram of the relationship of 50 the main pump, slippage tank, gear pump, main tank, pilot pump and servo-motor device.

Referring to the drawings in detail, 1 is the 55 end cover of the main hydraulic pump. This cover is connected by the bolts 2 to the main body ring 3 of the pump. In the end cover of

the pump there is supported on the bearings 4 a drive shaft 5. The exact details of the pump are not important, as they are shown in my U. S. Patent No. 2,021,354 issued November 19, 1935. This drive shaft is connected at the end 5 6 to any suitable source of motive power, such as an electric motor. Keyed to this shaft 5 is a drive pinion 7 retained in position by the key 8. This gear fits between the face plates 9 and 10 and within the ring 11, which form the gear 10 pump housing and gear drive. This assembly is mounted upon the face 1 of the main hydraulic pump by the retaining screws 12. The packing 13 is used to seal the outer cover plate 15 of the gear pump to the drive shaft 5.

There is mounted in the plates 9 and 10 a stub shaft or axle 14 and on this axle there are mounted the ball bearings 15, which in turn support the gear 16 that constitutes the other half of the gear assembly constituting the gear 20 pump. Fluid passageways 17 and 18 are provided leading from the slippage tank and leading to the main tank in order to remove the slippage from the main pump and its slippage tank. 19 indicates the gear pump chamber. 25

The gear 16 is also utilized as an intermediate driving gear which meshes with the gear 20 that is provided with a hub 21. This gear is keyed by the key 22 on the drive shaft 23 for a pilot pump 24 which may be a gear pump or any other 30 type of pump desired. This pilot pump 24 is mounted through the plate 25 and screws 26 upon the plate 10 of the gear pump.

In this manner when the electric motor drives the shaft 5 it drives the gear pump, consisting of 35 the gears 7 and 16 for the replenishment of the slippage in the main pump, and at the same time drives the pilot pump 24 supplying fluid pressure therefrom to the controls for controlling the main pump or other associated mechanism. 40 The speed of the driving shaft, therefore, proportions the supply of slippage fluid and pilot fluid according to speed of the master pump, so that the several pumps, which are independent upon one another for their successful 45 operation, are synchronized in their operation.

It will be understood that I desire to comprehend within my invention such modifications as may be necessary to adapt it to varying conditions and uses.

Having thus fully described my invention, what I claim as new and desire to secure by Letters Patent, is:

1. A pumping unit comprising a main hydraulic pump with a driven shaft, a housing adapted 55

- to be mounted on said main pump around said driven shaft, a gear adapted to be mounted on said driven shaft in said housing, a second gear meshing therewith supported in said housing, a third pump mounted on said housing having a drive shaft projecting therefrom into said housing, and a gear on said drive shaft of the third pump engaging with the second gear so as to be driven thereby, whereby the first two gears act simultaneously as a gear pump and as a driving means for the third pump.
2. In combination, a main pump, a driven shaft therefor, a main casing for the main pump, a supplementary casing mounted on one end of the main casing and surrounding a part of said driven shaft, a gear on said driven shaft within the supplementary casing, a second gear meshing therewith pivoted in said supplementary casing, said supplementary casing being arranged to form a gear pump chamber with an inlet and outlet in association with said gears, and means of connecting said pump chamber to a source of supply of fluid and to said main pump, a third gear meshing with the second gear and mounted within said supplementary casing, and a third pump mounted on said supplementary casing having a drive shaft projecting into the supplementary casing and supporting said third gear.
3. In a system of pumps, a casing, a main driven shaft, a main pump in said casing driven from said main driven shaft, a supplementary casing mounted on the main casing and around said driven shaft, said supplementary casing forming a pump chamber, a gear pump in said pump chamber driven by said driven shaft, a

third pump mounted on the supplementary casing having a drive shaft, and means driven by the gears of the gear pump drivingly engaging said drive shaft, said drive shaft being arranged in parallel relationship to the main driven shaft. 5

4. In combination in a pumping system, of a common power source, a common driven shaft and three pumps driven thereby and arranged in series, one of said pumps having pumping gears adapted simultaneously to pump fluid and to transmit the power delivered to it from another of the pumps to the third pump, whereby all three pumps are driven synchronously. 10

5. A pumping unit comprising a main hydraulic pump, power driving means therefor, a support adapted to be secured to said main pump, a detachable gear pump driven by said power driving means and mounted upon said support, and a pilot pump mounted on said gear pump and driven from one of the gears of said gear pump, whereby said gear pump serves simultaneously to pump fluid and to transmit power from said driving means to said pilot pump. 15 20

6. A pumping unit comprising power driving means, a main hydraulic pump driven by said driving means and having a casing with a casing end-plate, a gear pump mounted on said end-plate and adapted to be driven by said driving means, a pinion meshing with and driven by one of the gears of said gear pump, and a pilot pump driven by said pinion whereby the gear pump serves simultaneously to pump fluid and to transmit power from said driving means through the pump gearing to the pilot pump. 25 30
